ABSTRACT OF THE DISCLOSURE

A toy in which a child may sit while activating various instrumentalities from the sitting position, said toy comprising a base portion, a platform pivoted on top of said base portion, said platform including a seat and back rest, a boom mounted on the platform projecting upwardly and outwardly therefrom, a pulley at the free end of the boom, a drum rotatably mounted in the boom and having a crank handle which may be operated by the child while seated, a cord wound on the drum passing over said pulley and having load attaching means at its free end, a rotatable shaft manipulated by a crank on one end and attached to the base portion of the platform at the other end whereupon on rotation of said crank, said platform will turn in a 360 degree arc.

This invention relates generally to toys of the "sit-on" type in which a child seated on the toy itself may manipulate controls for performing various entertaining, educational and amusing functions.

It is an object of this invention to provide a toy as aforesaid, in which a child seated on the toy may perform at least two diverse functions each involving only one hand.

It is a further object of this invention to provide a toy as aforesaid, in which the child seated thereon may devote both hands to the performance of either of two functions.

It is a further object of this invention to provide a toy as aforesaid, which will be simple and easy to assemble, lightweight but strong in construction and so simple in operation as to be easily within the comprehension of the age group for which the toy is designed.

The above and other objects will be made clear from the following detailed description taken in connection with the annexed drawing, in which:

FIGURE 1 is a plan view of the toy as a whole;

FIGURE 2 is a side elevation of the toy as a whole; and

FIGURE 3 is a front elevation omitting only the uppermost parts.

It is well recognized that children enjoy imitating adult activities and the greater their own participation in the simulation of such activities, the greater the enjoyment. This is why the "sit-on" type of toy is vastly more appreciated than the small scale model, even though the small scale model be capable of the same manipulation as that of a sit-on toy. When the child can sit on the toy and actually participate in the manipulation and, at least to some extent, in the movements of the toy, the versimilitude of the simulation of adult activity is enormously increased. It was with these fundamental principles in mind that the toy of this invention was devised.

The toy is made of a base portion 10 which is generally frusto-pyramidal in form. A platform 12 forms a seat portion 14 with a back rest 16. The platform 12 is pivoted at 18 (FIGURE 1) to the upper portion of the base 10.

A boom portion generally designated at 20 has side members 22, each of which has an extension 24. The

2

extensions 24 overlie and are secured to the seat portion 14 of the platform 12. A pair of legs 26 form part of and depend from the base of the members 22 and support a foot rest 28. A winding drum 30 is secured to a shaft 32 which penetrates side members 22 and has at one end a crank 34. At the outer end of the side members 22 is a pulley 36 rotatably mounted on a shaft 38, with the shaft 38 penetrating the outer ends of the side members 22. A hoisting cord 40 is wound on the drum 30, passes over the pulley 36 and has at its free end a hook or other lifting device 42. The hook 42, of course, may be replaced by a bucket, a "clam shell" or any other suitable device.

In order that the platform 12 may rotate freely about the pivot 18, a number of guide rolls or wheels 44 are interposed between the underside of the platform 12 and the top of the base 10. Also fixedly secured to the top of the base 10 is a grooved pulley 46.

A shaft 48 is journaled between the extensions 24 of the side members 22 and has at its upper end a crank 50 and secured to its lower end a grooved pulley 52. A belt 54 passes around both pulleys 52 and 46 so that upon rotation of the crank 50, the platform 12 will rotate about its pivot 18 through a full 360 degrees in either direction. In fact, in any one operation, several complete revolutions in either direction may be made. The crank 50, it will be observed, is easily and conveniently within the reach of a child seated on the seat 14.

It will be noted that the arrangement described above places the child comfortably in a position which he may simultaneously operate cranks 34 and 50 or, if so desired, may use both hands to operate either. The weight distribution, including the weight of the child, is such that it will be almost impossible to unbalance the toy as a whole due to any conceivable weight which may be lifted by the hook 42.

Numerous constructional details differing from those disclosed herein no doubt will occur to anyone skilled in the art. The invention, therefore, is not to be limited to the precise details disclosed herein but only as set forth in the subjoined claims.

What is claimed is:

1. A toy on which a child may sit while activating various instrumentalities from the sitting position, said toy comprising: a base portion; a platform pivoted on top of said base portion, said platform constituting a seat and back rest for a child; a boom portion mounted on said platform and projecting upwardly and outwardly therefrom; a pulley at the free end of said boom portion; a drum rotatably mounted in said boom portion and having a crank handle operable by a child seated on said platform; a cord wound on said drum, passing over said pulley and having load attaching means at its free end, a shaft mounted in said platform for rotation about a vertical axis, said shaft having at one end a crank for manipulation by a child seated on said platform and having at its other end means connected to said base portion whereby rotation of said crank will turn said platform about said pivot relative to said base throughout a full 360 degrees.

2. A toy as set forth in claim 1, in which the means connected to said base portion comprises a pulley on said vertical shaft and a pulley on said base portion and a belt passing around both of said pulleys.

3. A toy as set forth in claim 1, in which a foot rest depends from said boom portion.

4. A toy as set forth in claim 3, in which the means connected to said base portion comprises a pulley on said vertical shaft and a pulley on said base portion and a belt passing around both of said pulleys.
